UNITED STATES PATENT OFFICE

NORMAN H. SAUNDERS, OF CHICAGO, ILLINOIS, ASSIGNOR, BY MESNE ASSIGNMENTS, TO ASSOCIATED ELECTRIC LABORATORIES, INC., OF CHICAGO, ILLINOIS, A CORPORATION OF DELAWARE

TELEPHONE SYSTEM

Application filed September 30, 1931. Serial No. 566,063.

This invention relates to telephone systems in general, particularly to systems in which common switching apparatus is employed in the establishment of connections, and is concerned primarily with arrangements for preventing the unnecessary occupation of such apparatus by defective lines.

Arrangements for preventing defective lines from holding common switching apparatus out of service are shown in the co-pending application of J. A. Burgener, Serial No. 455,541, filed May 26, 1930, and in applicant's Patent No. 1,834,649, granted Dec. 1, 1931, on which the present invention may be considered an improvement. In the prior systems, the equipment provided for locking out defective lines has been associated individually with the various lines. The greater part of this equipment will normally be idle as ordinarily only a relatively small number of the lines in a telephone system will be defective at any one time. It is the main object of the present invention to produce a lockout arrangement for use under the above conditions, which will be more efficient and economical than the prior arrangements. This object is attained by making the lockout equipment common to a number of lines thereby greatly reducing the amount of such equipment necessary to care for the normal requirements of a telephone system.

The various features of the invention, together with the operation of the equipment in a telephone system embodying the same, will be described in detail hereinafter, reference being had to the accompanying single figure of drawing. The embodiment of the invention in an automatic telephone system has been shown in the drawing by way of illustration. It will be understood, however, that the invention is not limited to use in such systems but may be applied equally well to semi-automatic and manual systems as will be readily apparent to those skilled in the art.

The drawing shows only sufficient of the equipment of a telephone exchange necessary for a clear understanding of the invention.

T represents an ordinary automatic substation telephone set. LS is a rotary, primary

lineswitch of the well known type terminating the line from the substation T. COR is a group of cut-off relays associated with a pair of trunk lines accessible to the lineswitch LS, and S is a Strowger type selector switch of which only the line and release relays have been shown. It will be noted that the pair of trunk lines accessible in the first and ninth bank positions of the lineswitch extend to the cut-off relay group and from this point a single four-conductor trunk extends to the selector. The circuit of the selector S has been modified slightly by the provision of an additional set of contacts for the release relay and an additional set of off-normal contacts for connecting the interrupter lead to the fourth conductor of the incoming trunk. The interrupter incidentally may be of any suitable type arranged to apply ground to the interrupter lead at certain regular intervals. The particular interval chosen will be determined by the local conditions of the system, for example, intervals of two minutes will permit the holding of the selector for a minimum of two minutes or a maximum of four minutes before the lockout equipment functions.

Proceeding now with the detailed description, it will first be assumed that the subscriber at substation T initiates a call and proceeds to dial in the usual way within the interval allowed for this purpose. Upon the initiation of the call, line relay 4 of the lineswitch LS operates over a loop circuit including contacts 9 and 13, conductors 1 and 2, and the loop at the substation. Relay 4 on operating, completes the test circuit at contacts 7 and prepares an operating circuit for relay 5 at contacts 8. If the trunk on which the wipers of the lineswitch is standing at this time is in use, wiper 16 will find ground on the test contact, which is extended over a circuit including contacts 11, 7, and 14, to energize stepping magnet 6, and shunt relay 5. The stepping magnet operates and interrupts its own circuit at contacts 14 and 15, on restoring advances the wipers one step. This operation is repeated as long as wiper 16 encounters grounded contacts. When an idle trunk is found the absence of ground

on the test contact permits relay 5 to operate in series with magnet 6 to extend the line conductors through to the selected trunk by way of contacts 10 and 12 and wipers 15 and 17. The original energizing circuit of 5 the line relay is opened at contacts 9 and 13 and the test wiper is connected to the upper terminal of relay 5 at contacts 30. Assuming that the selected trunk is the one comprising conductors 18-20, an operating circuit can now be traced for relay 51 of the selector S, from battery through the upper winding of the relay, conductor 21, contacts 34, wiper 15, contacts 10, line conductor 1, through the loop at the calling substation, line conductor 2, contacts 12, wiper 17, conductor 20, contacts 43, conductor 23, lower winding of relay 51 to ground. Relay 51 operates and completes a circuit for relay 52 at contacts 53. Relay 52 operates, prepares 10 the timing circuit at contacts 55, prepares the impulsing circuit at contacts 56, and at contacts 58 applies ground to release trunk conductor 48 which extends back by way of contacts 39, conductor 19, wiper 16 and contacts 30 to relay 5. Switching relay 5 of the lineswitch is held operated over this circuit after slow-releasing relay 4 restores which occurs a short time after its circuit is opened 15 by the operation of relay 5.

In case the calling subscriber dials before the interrupter applies ground to conductor 60, the selector will be stepped off-normal in the usual way, thereby interrupting the timing circuit at off-normal contacts 59. Accordingly, when the interrupter applies ground to the conductor 60 no operation of the lockout equipment will take place and the call will be extended through succeeding 20 switches in the usual manner responsive to further dialling.

It may occur, however, that the interrupter is in position at the time the selector is seized, or shortly thereafter, to apply ground to conductor 60, in which case a circuit will be completed by way of contacts 59 and 55, conductor 47, contacts 44, upper winding of two-step relay 32 to battery. Relay 32 will operate in its first step in which position contacts 46 are closed as indicated by the Roman numeral I, while the remaining contacts designated by the Roman numeral II remain in their normal positions. Ground is removed from conductor 60 after a short interval by the continued operation of the interrupter, thereby permitting relay 32 to operate fully over a circuit including its two windings in series, contacts 46 and grounded conductor 48. Relay 32 opens its initial energizing circuit at contacts 44 and extends conductor 47 through to the upper winding of relay 31 by way of contacts 45. In case the calling subscriber now dials, the selector will be stepped off-normal in the usual way 25 and the timing circuit will be interrupted

at contacts 59. The call will be further extended in the usual manner and no further operation takes place at the cut-off relay group, although relay 32 will remain energized until the connection is released and ground is removed from release trunk conductor 48 to which the relay remains locked. 70

In the event that a line becomes short-circuited or grounded, or in case a subscriber removes his receiver without dialling within a reasonable time, in the manner previously described, relay 32 will operate on the first application of ground to the timing circuit by the interrupter and will prepare the circuit for relay 31. After one complete cycle 75 of operation the interrupter will again apply ground to conductor 60, thereby energizing relay 31 over the previously traced circuit. Relay 31 bridges itself across the calling line loop by connecting its upper winding to conductor 18 at contacts 35 and by connecting ground to conductor 20 at contacts 42. The relay will remain operated over this circuit as long as the short-circuit remains on the line. The trunk comprising conductors 21- 80

23 which is accessible in the ninth position of the lineswitch LS will be separated from the trunk comprising conductors 18-20 accessible in the first position of the lineswitch LS by the opening of contacts 34, 39, and 43. The busying ground will be removed from test conductor 22 of the ninth position trunk by the opening of contacts 41 and this conductor will be connected through to release trunk conductor 48 at contacts 40. Ground will now be applied to test conductor 19 of the first position trunk at contacts 38 to hold up the switching relay of the lineswitch LS until the line is cleared. We now have the condition of the lineswitch having seized the first position trunk and being locked over this trunk while the tenth position trunk is now made accessible to other lineswitches and is connected through to selector S. The supervisory lamp L will glow as a circuit is closed at contacts 33, thereby notifying the exchange attendant that a line is locked out due to trouble. 95

In case the trouble is cleared from the line while the ninth position trunk is idle, the holding circuit for relay 31 will be opened and that relay will restore, thereby returning the trunk to normal condition, that is, with the first position trunk accessible to lineswitches and the ninth position trunk marked busied by ground at contacts 41. However, if another call is in progress on the ninth position trunk at the time the first position trunk is cleared, relay 31 will be held operated from ground on release trunk conductor 48, contacts 40 and 37, lower winding of relay 31 to battery. The first position trunk will accordingly be busied and when the connection over the ninth position trunk is finally released and ground is removed from the 100 105 110 115 120 125 130

release trunk conductor, relay 31 will restore and permit the release of the lineswitch over which the first position trunk was originally seized.

5 In case the connection extended over the ninth position trunk is one from a short-circuited line the selector will be held out of service as no provision is made for the lock-out of such connections. This, however, will 10 ordinarily be a rare occurrence since the number of lines which are defective at any one time in a system are usually few in number.

What is claimed is:

1. In a telephone system, a line, a first switch terminating said line, a second switch terminating a trunk accessible to said first switch, means controlled over the line for operating said first switch to connect the line with said second switch via said trunk, and 20 means revertively controlled from said second switch over said trunk for disconnecting the line from said second switch without releasing said first switch.

2. In a telephone system, a line, a first switch terminating said line, a second switch accessible to said first switch, means responsive to a condition placed on said line for operating said first switch to connect the line with said second switch, and means for disconnecting the line from said second switch and for maintaining said first switch in operated position until said condition is removed from the line.

3. In a telephone system, a line, a first switch, a second switch, means responsive to a particular condition placed on the line for operating said first switch to connect the line with said second switch, and means interposed between said two switches for freeing 40 said second switch from the connection and for maintaining said first switch operated as long as said particular condition exists on the line.

4. In a telephone system, a line, a first and 45 second switch, means responsive to a condition placed on said line for operating the first switch to connect the line to the second switch, a timing device, and means controlled by the timing device for freeing said second switch from the connection and for maintaining said first switch operated as long as said condition exists on the line.

5. In a telephone system, a line, a first and second switch, means responsive to the initiation 55 of a call on said line for operating the first switch to connect the line to the second switch, means in the second switch directly controlled over the line for setting the second switch, and means automatically operated responsive to a predetermined delay in setting the second switch for freeing the second switch from the connection and for maintaining the first switch operated.

6. In a telephone system, a line, a first and 65 second switch, means responsive to an un-

standard condition on the line for operating the first switch to connect the line to the second switch, and means automatically operated a predetermined time after the establishment of the connection for freeing the second switch from the connection and for maintaining the first switch in its previously operated condition until the unstandard condition is removed from the line.

7. In a telephone system, a plurality of lines, a switch individual to each line, a second switch accessible to all of said first switches, means responsive to a condition placed on one of said lines for operating its associated individual switch to connect the line to said second switch, means for preventing the connection of another line to said second switch while said connection is maintained, and means for disabling said connection preventing means and for maintaining said first switch operated as long as said condition exists on said one line.

8. In a telephone system, a plurality of lines, a switching device accessible to said lines in common, means for connecting any one of said lines to said device, means for preventing a second connection to the device while one connection exists, lockout means associated with said device, means for associating said lockout means individually with any one of the lines connected to said device, and means controlled by said lockout means for freeing said device for connection with other lines while said lockout means remains associated with said one line.

9. In a telephone system, a plurality of lines, a switching device common to said lines, means for connecting any one of said lines to said device, a relay adapted to be connected to any one of said lines which may be connected to said device, means for operating said relay, and means controlled by said relay for disconnecting said one line from the device and for maintaining itself operated over the line.

10. In a telephone system, a plurality of lines, a switching device accessible to said lines, means responsive to a condition placed on any one of said lines for connecting the line to said device, means responsive to said connection for rendering the device inaccessible to the remaining lines, a lockout relay common to said lines, contacts controlled by said relay for interrupting the connection between a line and said device and for rendering the device accessible to the remaining lines, and means controlled by said device for initiating the operation of said relay.

11. In a telephone system, a plurality of lines each terminating in an automatic switch, contact banks for said switches, a trunk line connected to two different positions of said banks and normally accessible in only one position, means responsive to a particular condition on any one of said lines

- for operating the associated switch to connect with said trunk via said one position, and means for disconnecting the trunk line from said one bank position and for rendering the same accessible to the remaining ones of said switches in the other bank position.
12. In a telephone system, a trunk line normally accessible in a particular position in the banks of a group of free hunting automatic switches, and means automatically operated under certain conditions for rendering the trunk line inaccessible in said particular position and accessible in a different position of said banks.
13. The combination with a trunk line normally accessible over one path, of means for rendering the trunk line inaccessible over said one path and accessible over a different path, and means controlled over the trunk line for rendering the trunk line inaccessible over said different path and for maintaining the trunk line inaccessible over said one path when a connection is extended to the trunk line over said different path.
14. The combination with a trunk line having two branches, of means normally effective to mark one of the branches busy, and means for removing the busy condition from said one branch and for disconnecting the other branch from the trunk line.
15. In a telephone system, a switching device, a trunk line terminating in said device, two branches for the trunk line, means for extending a connection to said device via the trunk line and one branch, and means automatically operated after a predetermined interval for interrupting said connection and for adapting said device to be connected with via the trunk line and said other branch.
16. The combination with a trunk line having two normally connected branches, of means for marking one of said branches busy, means for removing the busy condition from said one branch and for disconnecting the other branch from the trunk line, and means controlled over said other branch for maintaining the last said condition of the trunk line.
17. In a telephone system, a group of lines, a lineswitch for each line, contact banks for the lineswitches, a trunk line, two separate sets of contacts in each of said banks for the trunk line, and means responsive to the seizure of the trunk line via one of said contact sets and the lineswitch of a line on which an unstandard condition exists for making the trunk line accessible to the remaining lineswitches over the other of said contact sets.
18. In a telephone system, a group of lines, a lineswitch for each line, contact banks for the lineswitches, a trunk line, a plurality of separate sets of multiplied contacts in said banks for the trunk line, means responsive to
- a certain condition on one of said lines for operating the associated lineswitch to connect with said trunk line over one set of contacts, and a time controlled device for disconnecting said one set of contacts from the trunk line and for making the trunk line accessible to the remaining lineswitches over a different set of contacts.
19. In a telephone system, a group of lines, a switch for each line, contact banks for the switches, a trunk line, a first contact set and a second contact set in each of said banks for the trunk line, multiple connections between said first contact sets, multiple connections between said second contact sets, means responsive to the occurrence of certain conditions on one of said lines for operating the associated switch to connect with the trunk line via the first of said contact sets in its bank, means responsive to the establishment of said connection for preventing the connection of another switch to the first of said contact sets in its bank, and means for making the trunk line accessible to the remaining switches over the second contact sets in their respective banks while said one switch remains connected to said first contact set.
20. The combination with a trunk line having two branches, of means normally effective for making one of said branches inaccessible, means for extending connections from lines to the trunk line via the other of said branches, means operative when such connection is extended from a line on which an unstandard condition exists for disconnecting said other branch from the trunk line without disconnecting the line from that branch and for disabling the first said means.
- In witness whereof, I hereunto subscribe my name this 24th day of September, A. D. 1931.
- NORMAN H. SAUNDERS.
